SEWING MACHINE LENS OR THE LIKE

George M. Cressaty, New York, N. Y.

Application May 12, 1955, Serial No. 35,949

Term of patent 14 years

(Cl. D57—7)

Fig. 1.

Fig. 1 is a perspective view of a sewing machine lens or the like embodying my new design;

Fig. 2 is a side elevational view thereof;

Fig. 3 is a longitudinal section taken substantially through the center of the lens;

Fig. 4 is a top plan view thereof;

Fig. 5 is a section taken on line 5—5 of Fig. 2; and
Fig. 6 is a section taken on line 6—6 of Fig. 2.

I claim:

The ornamental design for a sewing machine lens or the like, substantially as shown.
